H. A. LINDSTROM

PAPER FASTENER

Filed Nov. 1, 1921

FIG - 1

FIG - 2

INVENTOR

HERMAN A LINDSTROM

BY

J. L. Rivers

ATTORNEY

UNITED STATES PATENT OFFICE.

HERMAN A. LINDSTROM, OF SEATTLE, WASHINGTON.

PAPER FASTENER.

Application filed November 1, 1921. Serial No. 512,035.

To all whom it may concern:

Be it known that I, HERMAN A. LINDSTROM, a citizen of the United States, residing at Seattle, in the county of King and State of Washington, have invented a new and useful Paper Fastener, of which the following is a specification.

My invention has reference particularly to improvements in paper fasteners of the flat metal variety adapted to be inserted through papers to be held, and then bent into operative position; and the objects I seek to achieve are, the provision of a fastener wherein the points of the prongs are covered when in place, thus affording one that presents no sharp points to catch on or mar adjacent objects; and, a special punch for this fastener, whereby openings may be pierced in said paper in a proper position 20 to accommodate the same.

In the accompanying drawings—

Figure 1 is a perspective of the fastener complete.

Fig. 2 is a plan view of the same as applied to and fastening sheets of paper.

Referring more particularly to the drawings, 1 designates the body of the fastener, made preferab'y of sheet brass, bent at one end into a right angular prong 2, and the other end bent into a right angular and shorter prong 3; 4 designates a slide of the same material mounted on the longer prong, the whole comprising the fastener complete. 35 5 denotes a pair of slits through sheets of paper, and diagonally located with reference to the corners thereof. These slits are made through the paper by the use of the punch heretofore referred to, and which I contemplate making the subject of another application.

To place the fastener in position, the prong portions are inserted to their limit through the slits from the under side of the paper, and the slide 4 then placed on the longer prong. The shorter prong 3 is then bent down in contact with the upper side of the paper, as indicated in Fig. 2, the longer prong 2 bent so as to contact with the first prong, and then the slide 4 is moved along 45 the prong 2 so as to embrace prong 3 and to cover the pointed terminal of prong 2. As shown in Fig. 2, the pointed terminal of prong 3 is covered by the prong 2, and the

slide covers the point of said last named prong, thus effectually covering the pointed terminals, and offering no sharp points for engagement with other objects when in use.

When the prongs are bent downward and the slide applied as indicated, the natural resiliency of the metal ordinarily is sufficient to keep the slide in place. If it is desired to further lock the slide, it can be done by striking out of the metal of prong 2 a small upwardly extending integral point 6, which will fit into a complementary recess in the slide, denoted by 7 in Fig. 2; said point and recess coming together when the slide is in the position shown in said figure.

In utilizing the ordinary brass fastener provided with a pair of contacting prongs adapted to be spread in opposite directions, the contiguous prongs act as a pivot on which the several sheets will turn, and the papers are not held securely in position. To make their use effective in this respect, two fasteners are necessary. In any use, the free ends of the prongs tear or catch on adjacent papers or objects. These objectionable features are particularly noticeable in placing or removing papers from files, wherein the second sheets are usually of material easily torn, and the exposed prongs catch on and withdraw papers other than the ones intended.

This fastener, by reason of its contact with the double slits in the paper, permits no pivotal play, and a single fastener at the corner of sheets of paper as shown, and as it is primarily intended to be used, is sufficient to hold the papers securely together and in alignment, at the same time exposing no sharp points. Its construction is such as to enable it to take the place of two of the usual brass fasteners, and to function in a better way.

I claim:

1. A paper fastener, comprising a body having at one end a prong angularly disposed, at the other end a longer prong angularly disposed and located oppositely of the first prong, and a slidable member mounted thereon, adapted to embrace said prongs and cover the free end of the longer prong when the longer prong is bent in operative position over the shorter prong.

2. A paper fastener, comprising a flat

body having at one end a prong disposed at right angles to the body, at the other end a longer prong, disposed at right angles to the body and located oppositely of the first prong, provided with an integral point adjacent its pointed terminal and projecting outwardly, a slideable member mounted thereon having an interiorly located recess to engage said point, said member adapted to embrace the shorter prong, to cover the free end of the other prong and to lock therewith, when the fastener is in operative position.

HERMAN A. LINDSTROM.
